ELECTRON DISCHARGE DEVICES, INCLUDING CAVITY RESONATORS

Louis Malter, Princeton, N. J., assignor to Radio Corporation of America, a corporation of Delaware

Original application October 5, 1948, Serial No. 52,908, now Patent No. 2,637,004, dated April 28, 1953. Divided and this application May 16, 1952, Serial No. 288,283

12 Claims. (Cl. 315—39.75)

This invention relates to improvements in electron discharge devices including cavity resonators, and particularly, such devices of the multi-cavity magnetron type.

The anode structure of a conventional multi-cavity magnetron is formed with an annular array of identical anode cavities which are open toward a central cathode and closed at the outer end and two sides to form substantially separate cavity resonators. The resonators are usually coupled together to some extent at the other two sides to form a single resonant system. It is well known that conventional multi-cavity magnetron oscillators with similar cavity resonators operate in any one of a number of different modes. Each of the different modes of operation involves a different instantaneous phase difference between the oscillations generated in adjacent resonators. It has been found that as a rule the most efficient and desirable mode of operation is that referred to as the "π-mode," in which the oscillations in adjacent resonators of the magnetron oscillator are 180° or π radians out of phase with each other, or, in other words, one set of alternate anode elements coupled to the resonators is at the maximum positive potential when the other or intermediate set of alternate anode elements is at the maximum negative potential. In order to achieve π-mode operation in conventional multi-cavity magnetrons, it is customary to electrically connect alternate anode elements together by means of low impedance conductors or "straps," to lock alternate anode elements and alternate resonators together into the same phase. One effect of these straps is to shift the oscillation frequencies of the various undesirable modes away from the frequency of the π-mode without affecting the latter, thus facilitating the elimination of the undesirable modes by causing the electric and magnetic field conditions suitable for the generation of the undesirable modes to lie far away from those which favor the π-mode. While the provision of such straps results in improved operation, it involves a considerable increase in the complexities of the device and in its mode of construction.

The primary object of my invention is to provide a multi-cavity magnetron with an improved structure for favoring π-mode operation.

Another object is to provide such a structure in which strapping is not required.

A further object is to provide a magnetron anode structure favorable to π-mode operation which is simple and easy to manufacture.

In accordance with my invention, the magnetron anode structures forming the cavities, instead of being alike, are constructed of two dissimilar forms arranged alternately along the periphery of the anode. The desired π-mode operation is achieved in cavity magnetrons having the cavities either closed on all sides or open on two sides by terminating alternate vanes short of the rear walls of the cavities, thus providing communication between adjacent cavities in pairs. Each pair of communicating cavities oscillates as a single cavity resonator.

The novel features which I believe to be character-

2

istic of my invention are set forth with particularity in the appended claims, but the invention itself will best be understood by reference to the following description taken in connection with the accompanying drawing, in which:

Figure 1 is a top section view, taken on the line 1—1 of Figure 2, of a multi-cavity electron discharge device incorporating one embodiment of my invention; and

Figures 2 and 3 are axial section views taken on the lines 2—2 and 3—3, respectively, of Figure 1.

Referring to Figures 1 to 3, I have shown a multi-cavity magnetron having an anode structure composed of a hollow cylinder 1 in the interior of which are mounted by suitable means an even number of radially-extending anode vanes 2 and 3. The vanes are uniformly distributed around the inner periphery of the cylinder 1 and terminate short of the central axis. The inner edges of the vanes 2 and 3 provide an annular series of anode elements surrounding a central cathode space. A disc 4 having a central aperture of approximately the same diameter as the cathode space is provided in each end of the cylinder 1 in contact with the adjacent side edges of the vanes 2, 3 and seated on annular shoulders 5 in the cylinder wall.

A conventional indirectly-heated cylindrical cathode 6, having end shields or "hats" 7, is axially mounted within the cathode space, to supply electrons therein for exciting the anode cavities during operation of the device. The vacuum envelope is completed by end plates 8 sealed to the ends of the cylinder 1. The cylinder 1, vanes 2 and 3 and discs 4 are made of good conducting metal, such as copper. Suitable means for maintaining a constant magnetic field parallel to the cathode within the cathode space are provided. Such means may consist of permanent magnet poles P, P' positioned closely adjacent the outer faces of the end plates 8, as shown in Fig. 2, or an electromagnet coil coaxially disposed with respect to the cathode axis. High frequency energy may be taken out of the magnetron by any suitable means, such as a coupling loop 9 linked with the axial magnetic flux of the electromagnetic field set up in one of the cavities and forming a continuation of the center conductor of a coaxial transmission line 10, as shown in Figure 1.

In operation, the anode structure and the cathode are connected to the positive and negative terminals, respectively, of a source of direct current potential and the radial electric field thus produced cooperates with the axial magnetic field to cause the electrons supplied by the cathode to form a rotating space charge within the cathode-anode space in the usual magnetron fashion. This space charge sweeps past the anode elements formed by the inner edges of the vanes 2 and 3 inducing high frequency voltages therein and setting up high frequency fields in the cavities.

Ordinarily, in an anode structure in which the cavities are closed on all sides the cavities are not coupled together except through the central cathode space into which the cavities open. According to my invention, alternate vanes 2 extend outwardly to the inner wall of the cylinder 1 and the intermediate vanes 3 terminate short of this wall, as shown, to form coupling apertures between adjacent cavities. As a result the cavities between adjacent vanes oscillate in pairs and adjacent pairs of cavities are 180° out of phase at every instant.

Each pair of adjacent anode vanes 2 and 3 and the portions of the discs 4 and cylinder 1 connected between the vanes constitute conducting walls defining or forming one of an annular series of anode cavities of equal radial length or depth, each cavity being closed on all sides except for the opening between the vane tips facing the cathode space and for the coupling aperture in one vane adjacent to the cylinder 1.

Due to the apertures thus provided between the coupling cavities at their rear or outer ends, the continuity of electric and magnetic components of the electromagnetic field set up in the cavities is such that the currents along the vane surfaces and the electric fields in the cavities must be directed as shown by the solid and dotted arrows 11 and 12, respectively, in Figure 1. This structure results in the interesting property of this magnetron that the electric fields at the anode elements formed by the inner edges of the vanes, where they are coupled to the rotating space charge in the cathode space, are similarly directed in pairs. Each pair of adjacent cavities on each side of the short vanes 3 oscillate together as a single cavity resonator and the pairs of cavities on each side of each long vane 2 oscillate 180° out of phase. Whereas conventional magnetrons in which adjacent cavities oscillate 180° out of phase in the desired π -mode require an even number of cavities, or $2n$ cavities, where n is an integer, in the form of magnetron shown in Figures 1 to 3 the condition that when one has made a complete circuit around the anode one must return to the same phase requires that for π -mode operation there must be an even number of pairs of cavities, or $4n$ cavities. These cavities form $2n$ cavity resonators.

It is apparent that the structure of my invention achieves substantially the same results as conventional strapping in favoring π mode operation, in a structure that is obviously much simpler and easier to manufacture than a strapped magnetron.

The present application is a division of my copending application Serial No. 52,908, filed October 5, 1948, now Patent No. 2,637,004, dated April 28, 1953, assigned to the same assignee.

While I have indicated only two embodiments of my invention, it will be apparent that my invention is by no means limited to the exact form illustrated or use indicated, but that many variations may be made in the particular structure used and the purpose for which it is employed without departing from the scope of my invention as set forth in the appended claims.

What is claimed is:

1. An electron discharge device anode structure comprising conducting wall means defining a series of adjacent cavities of equal depth, each cavity having a closed end and an open end and being closed on all sides except for said open end and for a coupling aperture in one side only located adjacent to said closed end and opening into the next cavity, the number of said cavities being $4n$, where n is an integer, whereby said anode structure can be excited in a mode with each pair of adjacent coupled cavities oscillating as a single cavity resonator.

2. An electron discharge device anode structure providing a series of cavities closed at one end and open at the other end and separated by conducting side walls, alternate separating side walls only being apertured adjacent to said closed ends only to couple said cavities together in pairs, and other conducting side walls connected between said separating side walls and closing the other sides of said cavities, the number of said cavities being $4n$, where n is an integer, whereby said anode structure can be excited in a mode with each pair of adjacent coupled cavities oscillating as a single cavity resonator.

3. An electron discharge device anode structure comprising an annular series of spaced parallel anode elements of equal length defining a central cathode space, the number of anode elements being $4n$, where n is an integer, and cavity resonators connected between alternate anode elements only, each of said cavity resonators including conducting wall means closing the outer end and at least two sides thereof.

4. An electron discharge device anode structure according to claim 3, including conducting wall means entirely closing said cavity resonators except for the spaces

between said anode elements opening into said cathode space.

5. An electron discharge device anode structure comprising conducting wall means defining an annular series of cavities closed at one end and opening into a central cathode space at the other end, said conducting wall means including radially-extending separating side wall portions of which alternate ones only are provided with apertures adjacent to said closed ends only for coupling adjacent cavities together in pairs and other radially-extending side wall portions closing the other sides of said cavities, the number of said cavities being $4n$, where n is an integer, whereby said anode structure can be excited in a mode with each pair of adjacent coupled cavities oscillating as a single cavity resonator.

6. A magnetron anode structure comprising a cylindrical conducting wall, an annular series of spaced parallel anode elements concentrically arranged within said cylindrical wall and defining a central cathode space, radially-extending conducting walls connecting alternate anode elements with said cylindrical wall, other radially-extending conducting walls extending from the other alternate anode elements toward but spaced from said cylindrical wall, and other conducting walls connected between adjacent radially-extending walls and closing the spaces therebetween, said walls defining a series of cavities open toward said cathode space and coupled together in pairs at the outer ends, the number of said cavities being $4n$, where n is an integer, whereby said anode structure can be excited in a mode with each pair of adjacent coupled cavities oscillating as a single cavity resonator.

7. A magnetron anode structure comprising an annular series of radially-extending conducting walls surrounding a central cathode space, a conducting wall surrounding said radially-extending walls and joined to alternate ones thereof and spaced from the other alternate ones, and other conducting walls joined to said radially-extending walls and closing the spaces therebetween, said walls defining a series of cavities open toward said cathode space and coupled together in pairs, the number of said cavities being $4n$, where n is an integer, whereby said anode structure can be excited in a mode with each pair of adjacent coupled cavities oscillating as a single cavity resonator.

8. A magnetron anode structure comprising an annular series of radially-extending conducting vanes surrounding a central cathode space, a cylindrical conducting wall surrounding said vanes and joined to the outer ends of alternate vanes, the outer ends of the other alternate vanes being spaced from said wall, and other conducting walls joined to the radially-extending edges of said vanes and closing the spaces between said vanes, said vanes and said walls defining an annular series of cavities open toward the cathode space and coupled together in pairs at their outer ends, the number of said cavities being $4n$, where n is an integer, whereby said anode structure can be excited in a mode with each pair of adjacent coupled cavities oscillating as a single cavity resonator.

9. A magnetron including: a anode structure comprising conducting wall means defining a series of adjacent cavities of equal depth, each cavity having a closed end and an open end and being closed on all sides except for said open end and for a coupling aperture in one side only located adjacent to said closed end and opening into the next cavity, the number of said cavities being $4n$, where n is an integer, whereby said anode structure can be excited in a mode with each pair of adjacent coupled cavities oscillating as a single cavity resonator; a cathode disposed adjacent to the open ends of said cavities; and means for establishing a constant magnetic field in the space between said cathode and said anode structure normal to the paths of electrons therebetween.

10. A magnetron including: an anode structure com-

prising an annular series of spaced parallel anode elements of equal length defining a central cathode space, the number of anode elements being $4n$, where n is an integer, and cavity resonators connected between alternate anode elements only, each of said cavity resonators including conducting wall means closing the outer end and at least two sides thereof; an elongated cathode axially disposed in said cathode space; and means for establishing an axial constant magnetic field in said cathode space.

11. A magnetron according to claim 10, including conducting wall means entirely closing said cavity resonators except for the spaces between said anode elements opening into said cathode space.

12. A magnetron including: an anode structure comprising an annular series of radially-extending conducting vanes surrounding a central cathode space, a cylindrical wall surrounding said vanes and joined to the outer ends of alternate vanes, the outer ends of the other alternate vanes being spaced from said wall, and other conducting

5
